CLAIM

The ornamental design for an anti-splash urinal screen, as shown and described.

DESCRIPTION

FIG. 1 is a top perspective view of an anti-splash urinal screen showing my new design;

FIG. 2 is a top plan view thereof;

FIG. 3 is a front elevation view thereof;

FIG. 4 is a right side elevation view thereof, the left side elevation view is a mirror image of the right side;

FIG. 5 is a bottom elevation view thereof; and,

FIG. 6 is a rear elevation view thereof.

The broken lines shown in urinal screen are for illustrative purposes only and forms no part of the claimed design.
